Primary Examiner — Robert M Spear*Assistant Examiner* — Marissa J Cash(74) *Attorney, Agent, or Firm* — Jeffer Mangels Butler & Mitchell LLP; Brennan C. Swain, Esq.(57) **CLAIM**

The ornamental design for an aircraft passenger service unit, as shown and described.

DESCRIPTION

FIG. 1 is a perspective view of an aircraft passenger service unit;

FIG. 2 is a front elevational view of the present invention shown in FIG. 1;

FIG. 3 is a rear elevational view of the present invention shown in FIG. 1;

FIG. 4 is a left side elevational view of the present invention shown in FIG. 1;

FIG. 5 is a right side elevational view of the present invention shown in FIG. 1; and,

FIG. 6 is a bottom plan view of the present invention shown in FIG. 1.

In the drawings the broken lines depict environmental subject matter only and form no part of the claimed design.
